UNITED STATES PATENT OFFICE

130,646

DESIGN FOR A BAG OR ANALOGOUS ARTICLE

George C. Adams, Brooklyn, N. Y., assignor to Standard Brands Incorporated, New York,
N. Y., a corporation of Delaware

Application September 30, 1941, Serial No. 103,583

Term of patent 14 years

To all whom it may concern:

Be it known that I, George C. Adams, a citizen of the United States, residing at Brooklyn, in the county of Kings and State of New York, have invented a new, original, and ornamental Design for a Bag or Analogous Article, of which the following is a specification, reference being had to the accompanying drawing, forming part thereof.

Figure 1 is a perspective view of a bag or analogous article showing one side and edge thereof; and

The different varieties of linings on the drawing are indicative of contrasting colors.

I claim:

The ornamental design for a bag or analogous article, as shown and described.

GEORGE C. ADAMS.
